US0D1102737S

(12) United States Design Patent (10) Patent No.: US D1,102,737 S
(45) Date of Patent: * Nov. 25, 2025

(54) PILL BOX

(71) Applicant: Apothecary Products, LLC,
Burnsville, MN (US)

(72) Inventors: Daniel Darst, Zimmerman, MN (US);
Julia Olson Augdahl, Prior Lake, MN (US)

(73) Assignee: Apothecary Products, LLC,
Burnsville, MN (US)

() Term: 15 Years

(21) Appl. No.: 29/939,399

(22) Filed: Apr. 26, 2024

(51) LOC (15) Cl. 03-01

(52) U.S. Cl.

USPC D3/203.3

(58) Field of Classification Search

(57) CLAIM

The ornamental design for a pill box as shown and described.

DESCRIPTION

FIG. 1 is a top front perspective view of a pill box showing the claimed design according to an embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a bottom rear perspective view thereof.

FIG. 9 is a top front perspective view of a pill box showing the claimed design according to an embodiment;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and

FIG. 16 is a bottom rear perspective view thereof.

FIG. 17 is a top front perspective view of a pill box showing the claimed design according to an embodiment;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof; and,

FIG. 24 is a bottom rear perspective view thereof.

1 Claim, 24 Drawing Sheets
